CLAIM

The ornamental design for a extendable strap, as shown and described.

DESCRIPTION

FIG. 1 is a top perspective view of a extendable strap in an undeflected position;

FIG. 2 is a front view of the extendable strap of FIG. 1;
FIG. 3 is a bottom plan view of the extendable strap of FIG. 1;
FIG. 4 is a back view of the extendable strap of FIG. 1;
FIG. 5 is a top plan view of the extendable strap of FIG. 1;
FIG. 6 is a right side view of the extendable strap of FIG. 1;
FIG. 7 is a left side view of the extendable strap of FIG. 1;
FIG. 8 is a bottom perspective view of the extendable strap of FIG. 1;

FIG. 9 is a top perspective view of the extendable strap of FIG. 1 in a deflected position;

FIG. 10 is a back view of the extendable strap of FIG. 9;
FIG. 11 is a perspective view of the extendable strap of FIG. 9 installed on a photographic flash unit; and,
FIG. 12 is a perspective view of the extendable strap of FIG. 9 installed on a photographic flash unit with an accessory secured to the strap.

The broken lines showing environment are for illustrative purposes only and form no part of the claimed design.

1 Claim, 5 Drawing Sheets
